UNITED STATES PATENT OFFICE.

LOUIS McCARTHY, OF BOSTON, MASSACHUSETTS.

INSULATING-JOINT.

1,170,920.

Specification of Letters Patent.

Patented Feb. 8, 1916.

Application filed June 1, 1914. Serial No. 842,007.

To all whom it may concern:

Be it known that I, LOUIS McCARTHY, a citizen of the United States, residing at Boston, county of Suffolk, State of Massachusetts,

have invented a certain new and useful Improvement in Insulating-Joints, of which the following is a specification, reference being had therein to the accompanying drawings.

My invention has for its object a new and improved insulator or insulating joint which shall be fireproof and which shall have the necessary mechanical strength and resistance to an electric current. The insulator described herein has these qualities and is also cheap and convenient to manufacture.

When insulating joints are being installed, it is customary to heat them in a Bunsen flame or torch until they are hot enough to melt gas-fitter's wax. When insulators of the ordinary type are treated in this way, the insulation is injured or impaired, the end members are loosened and the effectiveness of the joint is practically destroyed without the damage being apparent to the workman.

My object, therefore, has been to devise an insulator which can be treated in this manner without having its insulating properties impaired.

Various fireproof compounds which have the necessary electrical resistance for currents up to 5000 volts are available, but heretofore it has not been found possible to employ these materials successfully because if the joint is constructed to have the necessary mechanical strength it is found that it is likely to be ruptured electrically, particularly by the current passing from the proximate faces of the end members to the shell or to each other. The insulating joint embodying my invention has the necessary electrical and mechanical strength, and may be made of fireproof material. It is also very cheap to manufacture on account of the cheapness of the main body of insulating material.

The novel process by which my improved insulator is constructed forms the subject matter of a companion application filed by me on June 1, 1914, Ser. No. 842,008 to which reference may be had.

The invention will be fully understood by reference to the following description taken in connection with the accompanying

drawings and the novel features thereof will be particularly pointed out and clearly defined in the claim at the close of this specification.

In the drawings, Figure 1 is a side elevation of an insulating joint embodying my invention. Fig. 2 is a vertical section of the joint.

Referring now to the drawings, at 11 and 12, are indicated two end members tapped as shown at 13 and 14 for connection with a gas pipe or stud and the fixture. These end members are provided at 15 and 16 respectively with flanges preferably of irregular shape to afford greater adhesion to the insulating material which is molded about them.

At 18, is shown a steel shell having in-turned edges 19 and 20. The steel shell may be made of any convenient shape, but is preferably octagonal, in which case a wrench or other tool may be applied directly to the steel shell when the coupling is being put in place. The proximate faces 80 of the end members 11 and 12 are separated from each other by a washer 21 of insulating material. This washer is composed of superposed leaves of natural mica preferably united by a suitable insulating adhesive and effectually prevents the current jumping from one end member to the other. The end members are preferably cut away as shown at 22, and the washer preferably projects as shown at 23 into the annular 90 space thus formed. This construction is found to offer greater resistance to the electric current and to prevent it from jumping from one end member to the other through the bore in case dust or other foreign material accumulates at this point.

The interior of the shell 18 is lined with a tubular lining 24 of insulating material. This lining is composed of leaves of natural mica superposed upon each other and secured together with a suitable insulating adhesive as for instance liquid shellac to form a flat sheet which is rolled upon a mandrel to form the tube 24. This tube 24 is shaped to conform exactly to the shape of the interior of the shell between the in-turned flanges 19 and 20. If the shell is of non-cylindrical form the lining tube is of corresponding shape.

Molded about the flanges of the end members 11 and 12 are masses as of insulating material, these being designated 25 and 26.

2
These masses of insulating material are preferably composed of a mixture of silica, lime, clay and the like which can be "dry molded" while in a damp state. These 5 masses are of a size and shape to fill the interior of the tube 24 of insulating material which forms the lining of the shell 18. If the tube and shell are of non-circular shape, the blocks of insulating material will be 10 given a corresponding shape.

After the masses of insulation 25 and 26 have been molded about the end members, and while this insulation is still capable of being formed, the parts are assembled 15 within the shell and the whole subjected to heavy pressure in suitable dies which form the flanges on the shell. The said pressure drives the insulating material into every irregularity, and compacts the insulation 20 and forms the whole into a unitary structure. After the shell has been shaped as described, the entire insulator is vulcanized or baked to set and harden the masses of insulating material 25 and 26. This also has 25 the effect of softening the insulating ad-

hesive contained in the lining tube 24 and results in producing a more perfect union between the various parts of the insulator, thereby materially increasing the electrical resistance of the finished article. This 30 baking process also expels the moisture from the masses of insulating material 25 and 26.

What I claim is:

The improved insulator comprising flanged end members, masses of a fireproof insulating material molded about said end members, an insulating washer separating the proximate faces of said end members and masses of insulating material, a tube of mica surrounding said blocks of insulating 40 material, and a steel shell having inturned flanges curved over the shoulders of said masses of insulating material and securing the whole together.

In testimony whereof I affix my signature, 45 in presence of two witnesses.

LOUIS McCARTHY.
